SLIDE FASTENER

David Silberman, Brooklyn, N. Y., assignor, by
mesne assignments, to Universal Slide Fastener
Co., Inc., New York, N. Y., a corporation of
New York

Application December 15, 1937, Serial No. 179,843

4 Claims. (Cl. 24—205)

This invention relates to improvements in slide fasteners, being particularly directed to a novel tape and scoop assembly forming the opposing stringer series, and the method of making the 5 same.

Primarily, it is an object of this invention to provide in a stringer for a slide fastener, a tape and scoop assembly, wherein the tape is of a formation serving as a mounting for spaced 10 scoops and having portions thereof forming a permanent cover flap for the jaws of the scoops defining the exposed face of the stringers.

Specifically, it is an object of this invention to provide in a stringer incorporating a tape carrying spaced scoops, a tape folded intermediate of its ends to provide a scoop-mounting edge, with the two sections of the tape defined by the fold forming respectively a support element and a flap element, there being a "ladder-thread" formation on the flap element, so that upon folding the flap element over the scoops as mounted, a portion of the flap element serves as a cover for the jaws of the scoops on the exposed face of the stringer.

These and other advantages, capabilities and features of the invention will appear from the subjoined detailed description of one specific embodiment thereof illustrated in the accompanying drawing, in which

Figure 1 is a perspective view of a separable fastener assembly incorporating my invention.

Figure 2 is a perspective view of a stringer in the process of assembly.

Figure 3 is a plan view looking downward on 35 opposing stringers of the fastener assembly.

Figure 4 is a plan view looking upward upon opposing stringers of a separable fastener assembly.

Referring to the reference characters in the 40 drawing, numeral 10 represents a slide fastener assembly incorporating opposing stringers 11 and 11' mounting conventional scoops, and a Y-shaped channel slider 12 of the conventional type.

Referring particularly to Figure 2, the tape for 45 the stringer comprises a length of woven material having adjacent one of the edges thereof a "ladder" formation 13 provided in the weaving through the elimination of a series of longitudinally extending warp threads, the "ladder" formation comprising of spaced weft threads 14 defining substantially rectangular apertures 15.

The tape is folded intermediate its width to 50 form two sections, 16 and 17, and along each of 55 such sections, adjacent the fold edge 18 joining

the same, beads or cords 19 and 19' are disposed as by stitching.

A series of fastener elements or scoops 20 incorporating locking heads 21 having male and female members on opposite sides thereof, and symmetrical jaws or legs 22 and 22', are mounted in spaced relationship along the fold edge 18 of the tape, the jaws or legs 22 and 22' serving to enclose and clamp the beads 19 and 19' and the fold edge 18, for firmly mounting the scoops to the tape; in further assembling the stringers (reference being had to Figure 2), the tape section 16 having opposing wings 23 and 24 joined by the spaced weft threads 14 forming the rungs of the "ladder" formation 13 is displaced in the direction of the arrow there shown, about the fold edge 18 as an axis, for approximately 360° from its original horizontal position adjacent section 17. As a result of such displacement, the first step of which is shown in Figure 2, and the resulting product of which is shown in Figures 1, 3 and 4, wing 23 of section 16, which may be defined as the longitudinally extending portion between the "ladder" formation and the fold edge of section 16, is displaced so that it extends over 20 and covers jaws or legs 22 of the scoops adjacent thereto (see the dotted line showing at the front of Figure 2). The "ladder" formation is of such width that the heads 21 of the scoops are readily adapted to pass through the apertures 15 thereof, said apertures being preferably defined by the grouping together of two or three weft threads or rungs 14 in spaced relationship; the length of the threads or rungs being such that upon the passage through the "ladder" formation of the 25 scoop heads, the threads rest against the periphery of the fold edge 18 between the scoops and as shown in Figure 4 extend between the jaws or legs 22' of the scoops resting against the marginal portions of section 17 clamped by such 30 legs. The wing 24 of section 16 upon the completion of the displacement of said section is disposed in a position parallel to and adjacent section 17 of the tape, the wing 24 being attached to the section 17 forming the body of the stringer 35 by stitching indicated at 26.

It is obvious that various changes and modifications may be made to the details of construction without departing from the general spirit of the invention as set forth in the appended claims. 40

I claim:

1. A stringer for slide fastener assemblies, comprising a folded tape and scoops each having a head and leg portions carried thereon in spaced relationship, the legs of the scoops being mounted 45

to straddle and clamp the fold edge of said tape, the respective tape sections leading from the fold edge defining a body and a flap, a longitudinally extending ladder formation intermediate the flap section and providing apertures bounded by spaced threads in one direction only, the flap section being disposed through displacement about the fold edge as an axis, whereby a portion thereof serves to cover the legs of the scoops clamping the same and the threads of the ladder formation thereon rest between the scoops, the free end of the flap section being adjacent and parallel to the body section.

2. A stringer for slide fastener assemblies, comprising a folded tape, and scoops each having a head and leg portions carried thereon in spaced relationship, the legs of the scoops being mounted to straddle and clamp the fold edge of said tape, one of the tape sections leading from the fold edge having longitudinally disposed spaced apertures intermediate its width, said section being disposed through displacement about the fold edge as an axis, the longitudinal surface between the fold edge and the spaced apertures of said section covering the legs nearest said section of the interlocking members, the remaining portions of interlocking members being passed through the longitudinally spaced apertures, the free end of said section being disposed adjacent and parallel to the other tape section.

3. A stringer for slide fastener assemblies, comprising a folded tape and interlocking members each having a head and leg portions carried thereon in spaced relationship, the legs of the interlocking members being mounted to straddle and clamp the fold edge of said tape, one of the tape sections leading from the fold edge having longitudinally extending spaced apertures intermediate the width thereof and serving as a covering flap, said last named section being disposed through displacement about the fold edge as an axis, whereby the surfaces along its length between the fold edge and the spaced apertures thereon rest adjacent and cover the legs of the interlocking members nearest to said section, the spaced apertures of said tape section serving as sleeves through which the remaining portions of the interlocking members extend, the free end of said tape section being disposed adjacent the first named tape section.

4. A stringer for slide fastener assemblies, comprising a folded tape and scoops each having a head and leg portions carried thereon in spaced relationship, the legs of the interlocking members being mounted to straddle and clamp the fold edge of said tape, one of the tape sections leading from the fold edge serving as the body of the stringer, the other of said sections leading from the fold edge having spaced apertures separated by thread formations intermediate thereof and extending along its length, said last named section being disposed through displacement about the fold edge as an axis, whereby the surfaces along its length between the fold edge and the spaced apertures rest adjacent and cover the legs of the interlocking members nearest to said section, the spaced apertures serving as sleeves through which the interlocking members extend, the thread formations defining the spaced apertures being disposed between the interlocking members, and the free end portion thereof being disposed adjacent the first named tape section, said tape sections being stitched together along their length.

DAVID SILBERMAN.
